BRIEF BAG OR CASE

Filed April 8, 1927

S. H. Lifton INVENTOR
BY *Aaron L. Applebaum*
ATTORNEY

UNITED STATES PATENT OFFICE.

SAMUEL H. LIFTON, OF BROOKLYN, NEW YORK.

BRIEF BAG OR CASE.

Application filed April 8, 1927. Serial No. 182,086.

This invention relates to brief bags.

One of the objects of my invention is to provide a multiple pocket brief bag or case of the portable type such as employed by 5 attorneys, students or commercial men for carrying books, catalogues, legal instruments etc.

An object of my invention is to provide a brief bag or case particularly designed to 10 be constructed of leather or other suitable compositions of material having a more or less flexible nature and embodying a plurality of independent pockets or compartments therein which may be completely 15 closed yet permitting easy access thereto.

A continued object of my invention is to provide in a brief bag or case of the above 20 type an inside top pocket flap or closure adapted to cover and protect any inside pocket or pockets and permit access to any other of said pockets thereby increasing the multiplicity of uses to which the bag or case 25 may be employed.

A further object of my invention is to 30 provide in a multiple pocket or compartment brief bag or case and particularly to that type having provision in the bottom of said pockets or compartments means permitting it to stand upright, an inside strap 35 constructed and arranged to completely close the end openings of the central compartment or pocket when filled or partially filled.

To enable others skilled in the art to 40 which the invention pertains, that the same may be practiced in a varied manner to accomplish the purposes and objects above set forth and other objects, drawings depicting a preferred form are annexed hereto as illustrating an embodiment, and in which

Fig. 1 is a perspective view.

Fig. 2 is an end view.

Fig. 3 is a top view.

Fig. 4 is a sectional view showing a 45 tail of the top edge of one of the interior pocket sides.

Referring now to the drawings wherein 50 like reference characters designate corresponding parts throughout the several views, 5 designates the front and 6 the rear or back

wall of the bag or case which is usually constructed of leather or other flexible composition of material having good wearing qualities. The front 5 is stitched along its bottom 7 and along its sides 8 to the flexible 55 ends 9, 10, usually formed integral with the bottom 11 and preferably of a lighter stock of leather or other material.

The rear or back wall 6 is considerably longer than the front 5 so as to provide an 60 outside flap 12 which may extend completely over the top of the pockets or compartments and be locked in any suitable and well known manner in addition to being fastened by straps and buckles 12^a, 13, common 65 expedients in this type of bag or case. The ends 9, 10 are gathered and stitched as at 14 to the ends of the interior walls 15, 16 thus producing a multiple pocket or compartment bag or case, it being of course understood that the bottom of the said walls are also stitched to the bottom 11. The top 70 edge of each of the interior walls 15, 16 is provided with a reinforcing binding 17, preferably of leather or other wear resisting material stitched thereto as at 18 and which permits of the use of a lighter and less expensive stock and at the same time prevents the edge from being torn or damaged. Where a raw or free edge top is 75 present in a brief bag or case, due to the constant handling, removal from the insertion of various objects such as books, catalogues, papers etc. it is quite frequent that the wall is torn and damaged, thus destroying the idea, purpose and use of individual pockets and compartments. This objection is easily over come by binding and reinforcing the said top edge in the manner 80 above shown.

My invention is particularly related to 85 that class of brief bags or cases having provision in the bottom of one or more compartments affording a somewhat broad base and permits of the bag or case to stand upright. It is often desired to close or conceal 90 one or more compartments or pockets of the case, and therefor I have provided an interior closure flap 19 stitched along the bottom edge 20^a to the outside flap 12 and of a 95 100

length to extend into any one of the pockets to be fastened thereto such as by a snap fastener or extend to the outside and fastened in the same manner to the front 5. The flap 12 being considerably longer overlies the interior closure flap 19 as clearly indicated by Fig. 2.

One of the objections to the present type of brief bag or case resides in the fact that 10 when carrying heavy objects or bulky objects therein, due to the flexibility of the material from which the said bag or case is constructed, the top of the same has the tendency to sag or collapse with the result that 15 in its carrying condition, the bag or case has a distorted appearance since it is usually carried by means of a handle attached to the top. A more serious objection resides in the fact that the ends of the pockets or compartments 20 are not completely closed with the result that in stormy and bad weather, rain and snow can enter the several pockets and particularly the central pocket of the case.

In order to overcome these objections, I 25 have constructed the interior flap 19 so as to be slightly less in width than the outside flap 12. Attached to the inside of the central pocket or compartment and at each end thereof I have provided a narrow strap 20 which may pass on the outside of the edge of the flap 19 and through a slot 21 in the flap 12 whereby the end of said strap may be pulled up and bent over on the top of the case and fastened by means of a fastener 30 at a point adjacent the handle. Consequently, when the pockets are full for instance and the inside and outside flaps are fastened to the front 5, it will be seen that the side straps 20 being fastened to the central pocket, prevents the distortion of the 35 top of the bag and maintains the closure flaps snug and close to the top of the respective compartments or pockets completely closing the ends of the case.

While I have shown my invention and described the same with some degree of particularity, I realize that various changes and modifications are possible in the details illustrated. I therefore do not wish to 40 be limited and restricted to the exact form and details shown but reserve the right to make such alterations and changes as may fairly fall within and are commensurate with the subject being claimed.

Having shown and described my invention what I claim as new and desire to secure by Letters Patent is:

1. An article of the class described comprising a bag or case having pockets formed 45 by a plurality of walls therein, an inside flap adapted to be inserted within any of the said pockets and fastened to any of the walls thereof to close the top of any of said pockets and an outside flap overlying the inside

flap and adapted to be fastened to the front 55 of the bag or case.

2. An article of the class described comprising a bag or case having a front wall, a rear wall, bottom and ends, said front and rear walls being stitched to the bottom and 60 ends, said ends being gathered and connected by interior partitions forming a plurality of pockets, an inside flap attached to the rear wall and adapted to be inserted within any of the said pockets and fastened to 65 any of the partitions and an outside flap formed with the said rear wall overlying said pockets and inside flap and adapted to be fastened to the front of the bag or case.

3. An article of the class described comprising a bag or case having a plurality of pockets formed between a front wall, rear wall, ends and bottom, an inside flap for closing any of said pockets, an outside flap 85 overlying the inside flap and adapted to be fastened to the front wall and means fastened to the end walls for attachment to the top of the bag or case to close the ends of one of said pockets when the said outside flap is fastened to said front wall.

4. An article of the class described comprising a bag or case having a plurality of pockets formed between a front wall, rear wall, ends and bottom, an outside flap for closing said pockets and adapted to be fastened to the front wall and straps connecting the ends with the top of said bag or case for closing the ends of one of the pockets when the said outside flap is fastened to said front wall.

5. An article of the class described comprising a bag or case having a plurality of pockets formed between a front wall, rear wall, ends and bottom, an outside flap formed with the rear wall and adapted to be fastened to the front wall and straps attached to the ends of the central pocket and adapted to be fastened to the top of the bag or case for closing the ends of said central pocket when the outside flap is fastened to said front wall.

6. An article of the class described comprising a bag or case having a plurality of pockets formed between a front wall, rear wall, ends and bottom, an inside flap attached to the rear wall and adapted to be inserted within any of said pockets and fastened to any of the partitions thereof, an outside flap formed with the rear wall adapted to overlie the inside flap and adapted to be fastened to the front wall and straps connected to the ends of one of said pockets passing through slits in said outside flap and fastened to the top of the bag or case for closing the ends of one of said pockets.

7. An article of the class described comprising a bag or case having a plurality of pockets formed between a front wall, rear

wall, ends and bottom, an inside flap attached to the rear wall and adapted to be inserted within any of said pockets and fastened to any of the partitions thereof, the width of said inside flap being less than the width of said rear wall, an outside flap formed with the rear wall and adapted to overlie the inside flap and fastened to the

front wall and straps attached to the ends of one of said pockets and adapted to pass 10 outside the inner flap and through slits in the top of said bag or case and means for fastening the ends of said straps to the said top to close the ends of one of said pockets.

In testimony whereof I affix my signature.

SAMUEL H. LIFTON.
